A. H. CARRIER,

MEANS FOR CLOSING AND FASTENING WINDOWS.

APPLICATION FILED MAY 22, 1917. RENEWED DEC. 22, 1919.

1,330,237.

Patented Feb. 10, 1920.

INVENTOR —

A. H. CARRIER,

By *Knight Cook* gms

UNITED STATES PATENT OFFICE.

ALBERT H. CARRIER, OF ASHEVILLE, NORTH CAROLINA, ASSIGNOR OF ONE-HALF TO
EDWIN W. GROVE, OF ST. LOUIS, MISSOURI.

MEANS FOR CLOSING AND FASTENING WINDOWS.

1,330,237.

Specification of Letters Patent. Patented Feb. 10, 1920.

Application filed May 22, 1917, Serial No. 170,136. Renewed December 22, 1919. Serial No. 346,774.

To all whom it may concern:

Be it known that I, ALBERT H. CARRIER, a citizen of the United States of America, a resident of Asheville, in the county of Buncombe, State of North Carolina, have invented certain new and useful Improvements in Means for Closing and Fastening Windows, of which the following is a full, clear, and exact description, reference being had to the accompanying drawings, forming a part of this specification.

My invention relates to improvements in window fastening devices, and more particularly to means for lifting, closing and fastening sashes of the casement type. Considerable difficulty and inconvenience is usually experienced in closing and fastening hinged sashes, especially those hinged at the side. This is due partly to the fact that the sashes are usually warped to such an extent that their four margins cannot be readily forced into engagement with the window frame or casing, but the most undesirable condition is due to the fact that a sash hinged at the side will soon sag, and to close the window it is then necessary to force the sash upwardly at a point remote from the hinges, at the same time firmly forcing it to its closed position. The bottom rail of the sagged sash and the stile remote from the hinges usually strike the window frame before the sash reaches its closed position. It is therefore difficult to produce a tight joint at the four margins of the sash, and frequently difficult to lock or fasten the sash.

The main object of my invention is to provide a neat, simple and inexpensive means for lifting and at the same time firmly closing and fastening hinged sashes. The preferred form of the new device will lift the sash before the latter reaches its closed position, thereby preventing the sagged bottom rail from scraping or rubbing the sill, and during the lifting movement the sash is firmly forced to a fully closed position, wherein it is securely fastened to maintain the margins of the sash in firm engagement with the window frame. All of these results are preferably accomplished by merely turning a rotary operating device.

With the foregoing and other objects in view, the invention comprises the novel con-

struction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Fig. I is a fragmentary horizontal section showing a jamb, a portion of the sash or casement and the combined lifting, closing and fastening device.

Fig. II is a vertical section, the sash being omitted to more clearly show the recess in the jamb and the locking device mounted therein.

Fig. III is a vertical section taken approximately on the line III in Fig. I.

Fig. IV is a detail view showing the keeper in an edge of the sash.

Fig. V is a horizontal section, on a reduced scale, showing the hinge at one vertical edge of the sash or casement and the combined lifting, closing and fastening device at the opposite edge.

To illustrate the invention I have shown a window frame comprising jambs 1 and 2, and a sill 3. The sash, or casement, is provided with a stile 4 hinged at 5 to the jamb 2, and a stile 6 which lies adjacent to the jamb 1.

The combined lifting, closing and fastening device preferably comprises a keeper A mounted in an edge of the stile 6, a combined lifting, closing and fastening finger B extending into said keeper, and a rotary operating device C fitted to the finger B. The rotary operating device C is rotatably mounted in the jamb 1, and it may be rotated by turning a member 7 at the inside of the jamb 1. This member 7 is preferably a winged handle which may be readily turned at the inside of the window to impart a rotary movement to the operating device C, but it is to be understood that the invention is not limited to this particular means for rotating said device C. The finger B is preferably screwed onto a threaded end portion of the rotary operating device C, and when in service this finger projects into the keeper A, as shown in the drawings.

It will be observed that the finger B is mounted in a substantially L-shaped recess

- (Fig. II) in the jamb 1, said recess providing an approximately horizontal guideway and a depending pocket 8 at one end of said guideway. This guideway is lined with 5 metal and provided with an inclined wall 9 along which the finger B travels in lifting and closing the sash. The top wall of the keeper A has an inclined face 10 (Fig. IV) which normally rests upon the finger B. 10 The inclined bottom wall 9 of the guideway, and the inclined top wall of the keeper A, constitute lifting cams, the finger B being interposed between these inclines and adapted to coöperate therewith in lifting the sash. 15 More specifically stated, the finger B rests upon the inclined wall 9, and the inclined wall 10 rests upon the finger. When the screw threaded operating device C is rotated in one direction, the finger B travels 20 between the inclines 9 and 10 with the result of lifting the sash and at the same time forcing it into engagement with window frame.

When the finger B occupies the position shown in the drawings, it lies between the 25 inclines 9 and 10 and therefore cannot rotate with the operating device C. When the operating device is rotated, the finger B travels along the screw threads in a direction approximately parallel with the axis of the 30 screw. However, when the finger B registers with the pocket 8 (Figs. II and III) it is not confined between the inclines, and it can then turn with the operating device C so as to pass out of the keeper A and into 35 the pocket 8. The threaded end of the operating device C preferably engages the metal lining of the recess or pocket in the jamb and a pin 12 passing through said threaded portion serves as means for limiting 40 the movement of the finger B.

In opening the sash, the threaded operating device C is rotated so as to move the finger B toward the pocket 8, and when the finger reaches said pocket it turns with the 45 device C, thereby unlocking the sash by passing out of the keeper and into the pocket 8. The locking finger B then occupies an inoperative position, wherein it does not in any way interfere with the movement of the sash. 50 In closing the sash it is moved by hand to a position wherein the keeper A will register with the pocket 8 in the jamb 1. The locking device C is then turned so as to move the finger B into the keeper A. The finger B turns with the device C until said finger engages the top wall of the keeper A, and a continued rotary movement of the device C will cause the finger B to move in a direction approximately parallel with the axis of the 55 rotating screw, thus lifting the sagged portion of the sash, as previously pointed out, and at the same time firmly forcing the margin of the sash onto the window frame. By merely turning the operating device C, a 60 sagged and warped sash can be very easily 65

forced to a fully closed position, wherein it will be securely fastened by the closing device, which also serves as a sash fastener.

A screen S can be arranged in the window frame, as indicated by dotted lines in Fig. V, 70 and the combined lifting, closing and fastening device can be actuated without removing the screen.

I claim:

1. A casement window provided with a 75 combined lifting, closing and fastening device, said device comprising a keeper in one edge of the casement, a frame having a guideway which registers with said keeper when the casement occupies its closed position, a locking member extending from said guideway and into said keeper, said locking member being movable in said keeper and along said guideway so as to force the casement into engagement with 80 the frame, one of said parts having an inclined face providing a lifting cam whereby the casement is lifted when the locking member is forced along said guideway, and a rotary operating device whereby said locking 85 member is turned so as to pass into and out of said keeper, and said rotary operating device being free to turn independently of said locking member so as to force the latter along said guideway. 90

2. A casement window provided with a combined lifting, closing and fastening device, said device comprising a keeper in one edge of the casement, a frame having a guideway which registers with said keeper when the casement occupies its closed position, a locking member extending from said guideway and into said keeper, said locking member being movable in said keeper and along said guideway so as to force the 105 casement into engagement with the frame, said keeper having an inclined face providing a lifting cam whereby the casement is lifted when the locking member is forced along said guideway, and a rotary operating device fitted to said locking member, said locking member being movable in an arc of a circle with said operating device, so as to pass into and out of said keeper, and said rotary operating device being free to turn 110 independently of said locking member so as to force the latter along said guideway. 115

3. A casement window provided with a combined lifting, closing and fastening device, said device comprising a keeper in one 120 edge of the casement, a frame having a guideway which registers with said keeper when the casement occupies its closed position, a locking member extending from said guideway and into said keeper, said locking member being movable in said keeper and along said guideway so as to force the casement into engagement with the frame, said guideway having an inclined 125 face providing a lifting cam whereby the 130

casement is lifted when the locking member is forced along said guideway, and a rotary operating device fitted to said locking member, said locking member being movable in an arc of a circle with said rotary operating device so as to pass into and out of said keeper, and said rotary operating device being free to turn independently of said locking member so as to force the latter along said guideway.

4. A casement window provided with a combined lifting, closing and fastening device, said device comprising a keeper in one edge of the casement, a frame having a guideway which registers with said keeper when the casement occupies its closed position, a locking member movable between and fitted to the top wall of the keeper and the bottom wall of said guideway, one of said walls being inclined to provide a lifting cam whereby the casement is lifted when the locking member is forced along the guideway, and a rotary operating device fitted to said locking member, said locking member being movable in an arc of a circle with said rotary operating device, so as to pass into and out of said keeper, and said rotary operating device being free to turn independently of said locking

member so as to force the latter along said guideway.

5. A casement window provided with a combined lifting, closing and fastening device comprising a keeper in one edge of casement, a frame having a jamb provided with a guideway which registers with said keeper when the casement occupies its closed position, a screw threaded locking finger movable between and fitted to the top wall of the keeper and the bottom wall of said guideway, one of said parts being inclined to provide a lifting cam whereby the casement is lifted when the threaded locking finger is forced along said guideway, and a rotary operating device having a threaded portion fitted to the threaded portion of said locking finger, said locking finger being movable in an arc of a circle with said rotary operating device so as to pass into and out of said keeper, and said rotary operating device being free to turn independently of said locking finger to force the latter along said guideway in a direction approximately parallel with the axis of said rotary operating device.

In testimony that I claim the foregoing I hereunto affix my signature.

ALBERT H. CARRIER.
